CASING FOR A MACHINE FOR PINNING TAGS TO MERCHANDISE

Richard Hollerith, Jr., Upper Montclair, N.J., assignor to
Kimball Systems, Inc., a corporation of New York

Filed Mar. 24, 1964, Ser. No. 79,158

Term of patent 14 years

(Cl. D55—1)

FIG. 1

FIG. 2

FIG. 3

FIG. 4

FIG. 1 is a front perspective view of a casing for a machine for pinning tags to merchandise showing my new design;

FIG. 2 is a rear elevational view thereof;

FIG. 3 is a left side elevational view thereof; and

FIG. 4 is a top plan view thereof.

The dotted line showings in FIGS. 2, 3, and 4 are for illustrative purposes only.

I claim:

The ornamental design for a casing for a machine for pinning tags to merchandise, as shown and described.
